UNITED STATES PATENT OFFICE.

JOSEPH T. ROFFY, OF PITTSBURGH, PENNSYLVANIA.

DESIGN FOR A HEADLIGHT-LENS.

59,931.

Specification for Design.

Patented Dec. 6, 1921.

Application filed March 7, 1921. Serial No. 450,484. Term of patent 14 years.

To all whom it may concern:

Be it known that I, JOSEPH T. ROFFY, a subject of the Republic of Hungary, and residing at Pittsburgh, in the county of Allegheny and State of Pennsylvania, have invented a certain new, original, and ornamental Design for a Headlight-Lens, of which the following is a specification, reference being had to the accompanying drawing, forming a part thereof.

Figure 1 is a front view of a lens embodying this design. Fig. 2 is a sectional view of the same and Fig. 3 is a back view.

I claim:—

The ornamental design for a headlight lens, substantially as shown.

JOSEPH T. ROFFY.

Witness:

FRANCES B. BENTZ.
